UNITED STATES PATENT OFFICE.

CLARKE GUNTER, OF GUNTER, TEXAS.

RECEPTACLE FOR TOBACCO AND CIGARETTE PAPERS.

Application filed October 12, 1922. Serial No. 594,072.

To all whom it may concern:

Be it known that I, CLARKE GUNTER, a citizen of the United States, residing at Gunter, in the county of Grayson and State 5 of Texas, have invented certain new and useful Improvements in Receptacles for Tobacco and Cigarette Papers, of which the following is a specification.

My invention has for its object to provide 10 a receptacle of small dimensions and of neat appearance which may comfortably be carried in the user's pocket without unduly bulging the same and which receptacle is intended to hold a package of cigarette 15 papers and a quantity of tobacco.

Another object of the invention is to construct the receptacle in such a manner that the tobacco and cigarette papers have separate compartments.

20 Still another object of the invention is to make a receptacle sufficiently strong and durable to stand a great deal of wear and handling, but at the same time simple and cheap enough for the use of a wide range 25 of smokers.

One embodiment of the invention is illustrated in the accompanying drawings, and

Fig. 1 is a perspective view of a receptacle or pouch in closed position;

30 Fig. 2 is a longitudinal section along line 2—2 of Fig. 1;

Fig. 3 is a transverse section along line 3—3 of Fig. 2;

35 Fig. 4 is a plan view of the main part of the pouch developed;

Fig. 5 is a similar view of the front portion of the pouch;

40 Fig. 6 is a plan view of the strip constituting the sides and bottom of the pouch, and

Fig. 7 is a similar view of a square piece of material forming the small pocket intended to receive the cigarette papers.

45 In the drawings reference numeral 10 represents a substantially rectangular piece of leather or other pliable material forming the back and flap of the pouch. As seen in Figs. 1 and 2, the flap 11 is made to fold over the top of the pouch and reach approximately half way down the front thereof.

The front of the pouch is made of a piece of similar material 12, see Fig. 5, and a strip 13, see Fig. 6, constitutes the sides and

bottom of the pouch and is united with the 55 back 10 and the front 12 by means of a line of stitching 14 along the edges thereof. In this manner a comparatively large pocket 22 as best seen in Figs. 1, 2 and 3, is formed, open at the top, but which may be 60 closed by the flap 11 when folded over the opening. A package of tobacco 15 preferably wrapped in paper as at 16 fits snugly in the pocket formed in this manner.

As best seen in Figs. 1, 2 and 3, the edges 65 of the sides and bottom strip 13 are turned outward in order to facilitate the uniting of the parts, as it will be readily understood, that the stitching can be performed a great deal easier in this manner, than if 70 the edges of the side strip 13 were turned inward in the pouch.

Another piece 17 of the same material as the rest of the pouch, as seen in Fig. 7, is secured on the front portion 12 of the pouch by means of stitching 18 to form a thin pocket thereon. The stitching in this case is done without turning the edges of the piece 17 inwards, and this piece is preferably sewn on the front piece 12 before the 75 sides and back are attached thereto. This pocket is intended to receive a package of cigarette papers 19 and the pocket is placed in such a position that, when the package of cigarette papers is pushed down in the 80 bottom of the pocket, the upper portion of the pouch does not extend above the top of the upper edge of the large pocket, as seen in Fig. 2.

At 20 and 21 is shown the securing elements for the pouch and the usual glove snaps are preferable to any other kind of closing devices, but it is evident that a button or a strap with a clasp or buckle may be used, if so desired.

90 It will be evident that this pouch will make a very compact receptacle for tobacco and cigarette papers and that it will be sufficiently tight to retain necessary moisture in the tobacco.

95 It will also be evident that a thin package of matches might be inserted with the cigarette papers in the small pocket without making it unnecessarily bulky.

100 The upper edges of the pockets need have no stitches, when the pouch is made of leather or rubber, which also tends to make the pouch thinner.

A suitable size of the pouch has been found to be $3\frac{1}{4}$ inches wide, $4\frac{1}{4}$ inches in depth and $\frac{7}{8}$ inches thick, but it should be understood that larger or smaller pouches 5 may be manufactured to suit requirements.

The manner of uniting the edges of the different parts of the pouch clearly tends to make the construction stronger, than if the side strip 13 had its edges turned inward, 10 because the comparatively stiff edges formed of double layers of material will stand a great deal more wear, than if made any other way.

Another advantage of stitching the parts 15 together in this manner is that, when the pouch is only half filled, the sides 13 will fold inwardly instead of outwardly and in this manner decrease instead of increase the width and depth of the pouch. It also 20 makes the pouch completely collapsible when empty, in which case it will take very little room.

In order to keep the pouch tightly closed, 25 when it is not completely filled, one or two additional snaps 24 may be provided on the flap 11 or on the front piece 17, as seen in Fig. 4.

Having thus described the invention, what is claimed as new is:

A collapsible receptacle of the class described comprising substantially rectangular main front and back elements and a continuous side and bottom element having its edges out-turned and stitched respectively to the edge portions of the back and main front elements to form a pocket with stiff edges therewith, a pocket opening being situated at the short edges, a secondary front element of smaller dimensions than the said main front element and secured in a substantially central position thereon by stitching to form a small pocket therewith spaced away from all four edges of said main front element; a flap formed integral with said back element adapted to fold forwardly over said secondary front element, and means for adjustably securing the flap on said secondary front element, said means being concealed by said flap when in closed position.

In testimony whereof I affix my signature.

CLARKE GUNTER. [L. S.]
